Primary Examiner — Natasha Vujcic*Assistant Examiner* — Robert B Rieker(74) *Attorney, Agent, or Firm* — Notaro, Michalos & Zaccaria P.C.(57) **CLAIM**

The ornamental design for a solar garden light stick, as shown and described.

DESCRIPTION

FIG. 1 is a top, front perspective view of a solar garden light stick, showing my design therefor,

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines in the drawings illustrate portions of the solar garden light stick which form no part of the claimed design.
